[57] **CLAIM**

The ornamental design for an outsole for a snowboard boot, as shown and described.

DESCRIPTION

FIG. 1 is a top front and right perspective view of an outsole for a snowboard boot showing my new design, the broken lines showing portions of an outsole and boot throughout the views being for illustrative purposes only, forming no part of the claimed design; and the opposite perspective view being a mirror image except for more pronounced side curvature; FIG. 2 is a top plan view thereof;

FIG. 3 is a fragmentary right side elevational view thereof; FIG. 4 is a fragmentary left side elevational view thereof;

FIG. 5 is a fragmentary front elevational view thereof;

FIG. 6 is a fragmentary rear elevational view thereof; and,

FIG. 7 is a bottom plan view thereof.

The broken lines showing the toe and heel portions of the snowboard boot outsole in FIGS. 1-7 and the snowboard boot upper in FIG. 1 are for illustrative purposes only and form no part of the claimed design.
